UNITED STATES PATENT OFFICE.

MATTHEW W. ADAMS, OF CLEVELAND, OHIO.

BANDAGE.

1,363,075.

Specification of Letters Patent. Patented Dec. 21, 1920.

Application filed August 25, 1917. Serial No. 188,154.

To all whom it may concern:

Be it known that I, MATTHEW W. ADAMS, a citizen of the United States, residing at Cleveland, in the county of Cuyahoga and State of Ohio, have invented new and useful Improvements in Bandages, of which the following is a specification.

This invention relates to surgery, and more especially to bandages, and the object 10 of the same is to produce a first aid bandage by means of which a wound or injury can be quickly bound up or a dressing applied and held thereon, and the well known tendency of the bandage to become soaked with blood 15 is avoided.

This object is carried out by making one end of the bandage waterproof so as to overlie the wound or the dressing, and constructing the remainder of the bandage in 20 such manner that it will overlie and hold the water proof section in place.

Details are set forth below and shown in the drawings wherein—

Figure 1 is a perspective view of this 25 bandage as applied to the wrist.

Fig. 2 is a plan view of the bandage, and Fig. 3 is a similar view of an extension.

Fig. 4 is a perspective view of the bandage and extension connected.

The body of this bandage is a strap or 30 band 1 of leather, fabric or other suitable flexible material, and at one end the body is preferably continued into a pair of tongues 2 having perforations 3. At its other end a 35 suitable section 4 is rendered waterproof while yet remaining flexible, and this may be done by dipping this end of the band in or saturating or coating it with any appropriate waterproof liquid or compound, al- 40 though it is quite within the spirit of my in- vention to cover one or both faces and cer- tainly the inner face of this end of the band with a waterproof sheet as of rubber, or pos- sibly to sew or otherwise attach a rubber 45 band to this end of the body band. To the outer face of the body adjacent the water- proof section is attached a pair of buckles 5.

In use, let us assume that a soldier has 50 been injured in the wrist, and the wound is bleeding profusely. He places a wad of gauze or other surgical dressing on the

wound, lays the waterproof section of the bandage thereover, wraps the body of the bandage thence around his wrist, passes the tongues 2 through the buckles 5, and draws them up tight so as to fasten the whole in place. This holds the dressing on the 55 wound, prevents excessive and perhaps dangerous bleeding as would be the case if an artery had been severed, prevents the admission 60 of dirt or septic matter to the fresh wound, and—if the bandage is drawn up sufficiently tight—prevents in a large measure the loss of blood and the contamination 65 of his clothing and extraneous objects thereby. I do not wish to be limited particularly to the fastening devices shown and described, but the perforated tongues can be passed through and engaged with the 70 buckles by one hand and the structure shown 75 is perhaps as simple and serviceable as any.

In Fig. 3 is shown an extension member whose body is composed of a similar strap or band 11 having a pair of perforated tongues 12 at one end and a pair of buckles 15 near its other end, and the waterproof section is here omitted. Fig. 4 shows this extension as applied to the right end of the bandage proper as illustrated in Fig. 2, and the waterproof section 4 lies beneath or be- 80 hind the body of the extension. It could be applied over a wound on the side, for instance, and the entire bandage has now been extended so that it is long enough to reach around the waist. It is quite possible to 85 supply the bandage with a comparatively short main member 1 having the waterproof section 4, and one or two extension members so that the main member can be lengthened for use on a large limb or even around the 90 body.

What is claimed is:

A bandage comprising in combination an elongated member, a water proof section formed at one end of said member, straps 95 extending from the opposite end of said member and buckles secured to the member and spaced between the water proof end and the straps and in alinement with the latter.

In testimony whereof I affix my signature.
MATTHEW W. ADAMS.
